Primary Examiner — Ralf Seifert(74) *Attorney, Agent, or Firm* — Banner & Witcoff, Ltd.(57) **CLAIM**

The ornamental design for a tire repair kit, as shown and described.

DESCRIPTION

FIG. 1 is a front-top perspective view showing a tire repair kit according to a first embodiment showing my design;
FIG. 2 is a rear-top perspective view thereof;
FIG. 3 is a front-bottom perspective view thereof;
FIG. 4 is a rear-bottom perspective view thereof;
FIG. 5 is a front view thereof;
FIG. 6 is a rear view thereof;
FIG. 7 is a left side view thereof;
FIG. 8 is a right side view thereof;
FIG. 9 is a top view thereof; and,
FIG. 10 is a bottom view thereof.

The broken lines are included for the purpose of illustrating portions of the tire repair kit that form no part of the claimed design.
